UNITED STATES PATENT OFFICE.

JENNIE M. BODENSIEK, OF NEW YORK, N. Y.

ABDOMINAL SUPPORT.

Application filed August 11, 1922. Serial No. 581,041.

The present invention is directed to the provision of an improved form of abdominal or visceral support and has for its object to provide a device which has the required degree of stiffness and rigidity to support the various human organs in the desired positions and yet be so yieldable and flexible as not to interfere with or materially impede the bending or flexing of the body as in stooping, sitting or walking.

A further object resides in the provision of a device of this character which may be worn with the minimum discomfort and inconvenience.

Another object is to provide a device of the above class which completely encircles the body of the user and is provided with a substantially continuous front portion yet fastens at the front.

Other objects of the present invention will be hereinafter pointed out in the accompanying specification and shown in the drawings which show one embodiment of the invention.

In the drawings Fig. 1 is a front view of the device with certain portions broken away to show the interior construction.

Fig. 2 is a perspective rear view of the device.

Fig. 3 is a detail view of the main supporting member.

Fig. 4 shows an edge view of the lower part of the main supporting member. This figure shows a slightly thickened section of the spatulate shaped member at a point adjacent the minor axis of the elliptical end portion thereof.

In more detail, the support comprises a main body portion 10 which is in the form of a long band or strip of suitable flexible cloth or like material slightly broadened at the front at 11 and slotted at 12 to permit the passing of one end of the strip through the other end. Attached to the ends of the strips are the tapes 13 one of which carries a suitable buckle or other fastening device to permit the tapes to be drawn together and the band tightened. The construction of the band and the arrangement of the tapes and buckle obviate any metallic fastenings at the back of the user and also allow the band to be readily adjustable to any desired girth.

To provide the required reinforcement over the abdomen I provide a novel supporting member which is shown in Fig. 3. This support is comprised of two joined parts one

(17) shaped in the form of a spatula having a substantially elliptical end portion 14 and an upwardly extending integral strip 15. Attached to spatula part is a second strip 16 preferably of substantially rectangular shape. The strip 16 is secured to the spatula by rivets which are disposed substantially as shown leaving the ends free to flex back and forth. Preferably the spatula part is thickened very slightly adjacent the minor axis of the elliptical end to provide additional stiffness as shown at 20 in Fig. 4. The lower end or tip of the elliptical portion is made as thin as possible to secure the maximum of flexibility.

Preferably the support parts are made of steel or like flexible material which may be rubberized or otherwise protected against rust, the spatulate member providing support transversely and the strip member providing support longitudinally.

After assembly the support is sewn in place in a cloth pocket 18 upon the band. In placing the support in position the strip 16 is disposed away from the body of the user.

Suitable auxiliary stay strips 19 are also provided which are secured in the usual cloth pockets upon the interior of the band. The stays preferably extend in converging direction from the main supporting member and terminate slightly short thereof to permit free flexibility between the main and auxiliary supports.

After the stays and supports are placed in position the usual padding 20 may be provided at desired points.

The main stay or support 17 is particularly adapted to properly support the internal organs in an effective manner and at the same time its construction is such as to permit a free flexing or bending thereof so as to readily conform to the contour of the wearer. The supplementing strip 16 provides additional vertical stiffness to the spatula member but on account of its being free therefrom at the ends it does not impede the free bending of the ends of the main stay member.

The main stay 17 is of such shape that the lower end or tip thereof tapers in its lateral width to its lowermost point. The point, however, is not sharp but is slightly curved and rounded to avoid sharp edges. This arrangement and shape of the stay 17 permits the lower tapering laterally thin tipped por-

tion of the stay to extend to and be supported upon the pelvic bone of the wearer. This construction further provides a stay member of such shape that it will not ride up upon the wearer assuming a bending or sitting posture. On the other hand, the stay member unlike previous stay members of different configuration remains and maintains its lowermost position with the tip resting upon the pelvic bone irrespective of the position of the body of the wearer. The configuration of the lower end of the elliptical portion of the stay which is of orange spoon configuration or shape prevents the above described undesirable action. This undesirable action heretofore has occurred when the lower portions of the stay were of broad configuration either in the form of rounded stay members or of stay members having relatively square ends. The comfort to the wearer and the preventing of the undesirable riding up action is further secured by the provision of a stay assembly which is comparatively freely flexible upon horizontal axes. At the same time the desirable supporting properties are secured by so constructing the stay that it is flexible to a less degree if at all about vertical axes. The construction of the stay with a thick section at the minor axis of the ellipse and with a relatively thin lower end contributes to this action of the stay when in use. It will be further understood that the supplementary stay member 16 is disposed upon the outside of the main stay member and away from the body of the person wearing the corset or support. Thus the inner surface of the spatulate shaped member 17 affords a shield having a smooth inner surface without cooperating inner parts such as 16 which, if next to the body of the user, would cause abrasion and pinching. The present stay is therefore comfortable to the user and at the same time adapted to render the desired support.

While I have shown my invention associated with a band type of abdominal support it will be understood that its use is not limited to such forms. The invention may readily be applied to corsets and the like.

The tapes 13 are so located with respect to the band as to extend across the point of greatest girth. This feature in connection with the slotted part 12 affords freedom of movement to the wearer and prevents vertical displacement of the tapes and band when in use.

The band at the top extends substantially straight across, and the lower part 11 is extended downwardly and the lower edges of the band at each side are curved upwardly to give the maximum freedom of movement to the limbs of the wearer.

What I claim is:

1. An abdominal support, comprising in combination, with a fabric body portion to

encircle the trunk, of a stay or supporting member carried thereby for supporting the abdomen said member comprising an element of spatulate shape with a shank portion and an integral elliptical lower end and 70 a supplementary element attached to the aforesaid element at a place near the end of said elliptical lower end and having its ends freely displaceable with respect thereto and in cooperation with and protected from 75 contact with the body of the user by the shank portion and lower elliptical end portion of the stay member.

2. An abdominal support comprising in combination with a fabric body portion, of a one piece spatulate shaped element carried in a pocket therein to support the visceral organs, said element having an integral shank and end portion, said end portion having an elliptical configuration provided 85 with a thin gradually tapering laterally narrow lower extension of orange spoon configuration to extend to and rest upon the pelvic bone of the user, and supplementary stay members carried by the said body portion and disposed in converging relation to the lower end of the spatulate shaped element and spaced therefrom to permit flexure.

3. A stay for supporting the organs of the abdomen comprising a one piece spatulate shaped element having a shank portion and also a substantially elliptical lower end portion serving as a transverse support member, and a supplemental longitudinal support element attached thereto remote from the ends of said supplemental element and extending longitudinally therewith with free ends sliding respectively upon the surface of said shank and upon the elliptical lower end portions to provide flexure, said spatulate shaped element having a length greater than the length of said supplemental element whereby the spatulate acts as a shield to protect the wearer from the ends of the supplemental member and affords a sliding surface for the supplementary stay member.

4. A stay member for supporting the organs of the abdomen comprising an inwardly smooth spatulate shaped element having a shank portion and an integral lower elliptical end portion, said end portion having a thin gradually tapering laterally narrow lowermost end of orange spoon configuration adapted to rest upon the pelvic bone of the wearer whereby the stay member retains its proper vertical position upon the user bending or assuming a sitting posture.

5. A stay member for supporting the organs of the abdomen comprising a spatulate shaped element having a shank portion and an elliptical lower end portion, said elliptical lower end portion being thickened adjacent its minor axis and having the lower end at the end of the major axis of the ellipti-

cal portion relatively thin to provide relative rigidity against bending about the vertical axis and to permit flexibility and relatively free bending movements about horizontal axes.

6. The invention set forth in claim 5 in which the spatulate shaped element comprises an integral shank and an elliptical lower end portion, said elliptical lower end portion having a laterally narrow tapering extension integral therewith and adapted to extend downwardly from the

main body of the end portion and to be supported upon the pelvic bone of the user, said end portion having free flexibility on horizontal axes whereby by said free horizontal flexibility and tapering configuration said stay member retains its position upon the pelvic bone and does not ride up upon the user assuming a sitting or bending posture.

15 20
In testimony whereof I hereto affix my signature.

JENNIE M. BODENSIEK.
